CLAIM

The ornamental design for an appearance measurement instrument, as shown and described.

DESCRIPTION

FIG. 1 is a top front end perspective view of an appearance measurement instrument.

FIG. 2 is a top back end perspective view thereof.

FIG. 3 is a bottom left side perspective view thereof.

FIG. 4 is another top front end perspective view thereof.

FIG. 5 is a front end view thereof.

FIG. 6 is a back end view thereof.

FIG. 7 is a right side view thereof.

FIG. 8 is a left side view thereof.

FIG. 9 is a top view thereof; and,

FIG. 10 is a bottom view thereof.

The broken lines in the figures illustrate portions of the appearance measurement instrument that form no part of the claimed design.

1 Claim, 10 Drawing Sheets
